CLAIM

The ornamental design for a fishing lure, as shown and described.

DESCRIPTION

FIG. 1 is a perspective view of a fishing lure configuration showing my new design; the broken lines depict environmental structure for illustrative purposes only and form no part of the claimed design;

FIG. 2 is a side elevation view of the fishing lure configuration of FIG. 1, the side elevation view of the opposing side being identical thereto; the broken lines depict environmental structure for illustrative purposes only and form no part of the claimed design;

FIG. 3 is a longitudinal section view shown along line 3-3 of the fishing lure configuration of FIG. 1; the broken lines depict environmental structure for illustrative purposes only and form no part of the claimed design;

FIG. 4 is a perspective view of an alternate fishing lure configuration showing my new design; the broken lines depict environmental structure for illustrative purposes only and form no part of the claimed design;

FIG. 5 is a side elevation view of the fishing lure configuration of FIG. 4, the side elevation view of the opposing side being identical thereto; the broken lines depict environmental structure for illustrative purposes only and form no part of the claimed design;

FIG. 6 is a longitudinal section view shown along line 6-6 of the fishing lure configuration of FIG. 4; the broken lines depict environmental structure for illustrative purposes only and form no part of the claimed design;

FIG. 7 is a perspective view of an alternate fishing lure configuration showing my new design; the broken lines depict environmental structure for illustrative purposes only and form no part of the claimed design;

FIG. 8 is a side elevation view of the fishing lure configuration of FIG. 7, the side elevation view of the opposing side being identical thereto; the broken lines depict environmental structure for illustrative purposes only and form no part of the claimed design; and,

FIG. 9 is a longitudinal section view shown along line 9-9 of the fishing lure configuration of FIG. 7; the broken lines depict environmental structure for illustrative purposes only and form no part of the claimed design.
